United States Patent

Des. 235,641
Patented July 1, 1975

235,641

ACTUATOR FOR A VALVE

Linwood P. Erickson, Warren, R.I., assignor to
G. W. Dahl Company, Inc., Bristol, R.I.

Filed June 5, 1973, Ser. No. 367,351

Term of patent 14 years

Int. Cl. D23—01

U.S. Cl. D23—19

FIG. 4

FIG. 1 is a front elevational view of an actuator for a valve embodying my new design;

FIG. 2 is a side elevational view thereof;

FIG. 3 is a top plan view thereof;

FIG. 4 is a bottom plan view thereof.

The broken line representation of a valve in FIGS. 1, 2 and 4 is for purposes of illustration only.

I claim:

The ornamental design for an actuator for a valve, substantially as shown and described.
